UNITED STATES PATENT OFFICE.

HARRY GULLIVER, OF SOUTH YARRA, NEAR MELBOURNE, VICTORIA, AUSTRALIA, ASSIGNOR OF ONE-HALF TO HENRY GREER ROBINSON, OF MELBOURNE, VICTORIA, AUSTRALIA.

SEMAPHORE-INDICATOR FOR ELECTRIC SIGNALING.

SPECIFICATION forming part of Letters Patent No. 703,957, dated July 1, 1902.

Application filed April 23, 1902. Serial No. 104,367. (No model.)

To all whom it may concern.

Be it known that I, HARRY GULLIVER, builder, a subject of the King of Great Britain, residing at No. 411 Chapel street, South Yarra, near Melbourne, in the State of Victoria and Commonwealth of Australia, have invented an Improved Semaphore-Indicator for Electric Signaling on Railways, Tramways, and the Like, of which the following is a specification.

This invention relates to electric signaling on railways, tramways, and the like, in which communication is established either between fixed stations but more particularly between fixed signal boxes or cabins and the moving locomotive or tram-car. Its object has been to simplify the indicator mechanism and render same reliable and certain in action and to dispense with mechanical resetting or adjustment after having indicated a signal.

In order to facilitate a ready understanding of the invention, reference is now made to the drawings, in which—

Figure 1 is a front elevation of the indicator with the door open and parts removed, and Fig. 2 is a perspective sketch of the actuating mechanism.

For the sake of illustration it will be presumed that the indicator is fitted in the cab of a locomotive and that communication has been established with the signal-box by completing a circuit, say, by a brush on the locomotive contacting with a wire or conductor running parallel with the rails in manner known.

A B represent the terminals of the indicator-circuit, which is completed by wire C, relay D, wires E E, electromagnet F, and wires G G to terminal B. The usual bell or alarm circuit H is also coupled up, as shown, communicating with the battery J.

K represents an oscillating horseshoe magnetic armature, the ends of which are approximately in line with the center of the core of the electromagnet F, said armature being swung slightly out of center, as shown, so that normally the semaphore will be horizontal or at "danger." The rocking bar L, carrying the armature K, is mounted in bear-

ings M M. Attached to said rocking bar L is an upwardly-extending lever-arm N, connected by a link O to a short crank-arm P, rigidly mounted on a rod or spindle Q, to which the semaphore R, having an adjustable counterweight S, is secured, a plate T being fixed behind said semaphore to form a suitable background.

The full lines in Fig. 1 show the mechanism in its normal or danger position, the semaphore being visible through the window or view-hole U in the hinged door V.

When it is desired to give the "all-right" signal, the current to the terminals A B is reversed by means of any convenient form of reversing-switch, as W, connected to the signal-lever, and the current flowing in the opposite direction oscillates the horseshoe-armature to the position indicated in dotted lines, thereby causing the semaphore to fall to the all-right position through the medium of the actuating levers and arms.

It will be understood that should any breakage by accident take place in the circuit the semaphore will remain in its horizontal or danger position, notwithstanding the reversal of the switch, thus indicating at once that the mechanism is out of order. On the other hand, it is impossible to show the all-right signal except by reversing the switch. Thus the above-described indicator is reliable and certain in its action.

Having now particularly described and ascertained the nature of my said invention and in what manner the same is to be performed, I declare that what I claim is—

1. A semaphore-indicator for electric signaling on railways, tramways and the like, consisting of an electromagnet, an oscillating horseshoe magnetic armature, a rocking bar carrying said armature, an upwardly-extending lever-arm on said rocking bar, a rod or spindle having a crank-arm thereon, a semaphore carried thereby, and a link connecting the crank-arm on said rod or spindle with said lever-arm, substantially as described.

2. In indicators for electric signaling on railways, tramways and the like, an electromagnet, an oscillating horseshoe magnetic

armature mounted slightly out of center, with its legs on either side of said electromagnet, the ends being approximately in line with the center of the core, a signal and means connected to said armature for actuating a signal substantially as specified.

In testimony whereof I have hereunto set

my hand in presence of two subscribing witnesses.

HARRY GULLIVER.
